CLAIM

An ornamental design for the battery control module, as shown and described.

DESCRIPTION

FIG. 1 is a first perspective view of an embodiment of our new battery control module;

FIG. 2 is a second perspective view of the design of FIG. 1;

FIG. 3 is a front view of the design of FIG. 1;

FIG. 4 is a top view of the design of FIG. 1;

FIG. 5 is a bottom view of the design of FIG. 1;

FIG. 6 is a left hand side view of the design of FIG. 1; and,

FIG. 7 is a right hand side view of the design of FIG. 1.

The broken lines in the above described FIGS. 1- 7 are for illustrative purposes only and form no part of the claimed design.
